(57) **CLAIM**

The ornamental design for a powered rotary tool, as shown and described.

DESCRIPTION

FIG. 1 is a side view of the powered rotary tool incorporating my new design.

FIG. 2 is a front view.

FIG. 3 is a top view.

FIG. 4 is a side view opposite of the side shown in FIG. 1.

FIG. 5 is a rear view.

FIG. 6 is a bottom view.

FIG. 7 is a top perspective view; and,

FIG. 8 is a top perspective view of the side opposite of FIG. 7.
